HARRY G. BLANCHARD, OF BUFFALO, NEW YORK

HAIRPIN

Application filed December 17, 1932. Serial No. 647,763.

This invention relates to hairpins made of resilient material, and which are retained in the hair by a clasping or spring action.

The objects of this invention are to provide an improved hairpin which is so constructed that it will be more securely held in the hair without subjecting the hair to as much pressure or clamping action as pins heretofore made; also to provide a pin of this kind which is constructed to provide ample space between the legs of the pin for the enclosure of the hair without causing the hair to force the legs of the pin apart; also to provide a pin of this kind on which the outer surfaces of the legs are substantially free from projections or outwardly extending corrugations, which projections or corrugations in pressing against the head are apt to cause discomfort; also to provide a pin of this kind which is less visible in the hair than pins heretofore made; also to improve the construction of hairpins of this kind in other respects hereinafter specified.

In the accompanying drawing: Fig. 1 is a side elevation of a pin embodying this invention.

Fig. 2 is a face view thereof.

Fig. 3 is a side elevation of a pin of slightly modified form.

Hairpins made in accordance with my invention are preferably formed of resilient material preferably having somewhat greater width than thickness, and the cross section of the material may be rectangular, half round, half elliptical, or other shape. If desired, the pin may also be made of material of square cross section. The material from which they are made is bent to form a loop A terminating in a pair of legs B and C, the pin being preferably so bent that a flat face of the material lies on the insides of the legs. These legs are so formed that the major portions of the length thereof are spaced apart and may, for example, extend substantially parallel to each other. One or both of the legs of the pin is provided with one or more projections extending inwardly or toward the other leg. These projections may be of any suitable or desired form, and in the construction illustrated in

Figs. 1 and 2, they are of curved or substantially semi-circular form. In the particular construction illustrated in Figs. 1 and 2, the leg B is provided with two of these projections 6 and 7, and the other leg C is provided with a projection 8, the projections being preferably arranged to be substantially equidistant lengthwise of the pin. In the construction shown in Fig. 3, the hairpin is similar to that shown in Figs. 1 and 2, except that the legs are slightly curved to conform approximately to the shape of the head, and projections 9, 10 and 11 are provided on this pin which are of slightly different form than those shown in Fig. 1. In both of the constructions, the projections formed on the legs of the pins are such that the projections form wedge-shaped recesses between the legs of the pin into which hair would be wedged, if the pin tended to move lengthwise out of engagement with the hair.

In constructing the pins, the last projections 7 and 10 are preferably formed at a slight distance from the ends of the pins so that the ends of the pins will be separated. This greatly facilitates the separating of the legs of the hairpin to insert the same into the hair.

The pin described overcomes the objection heretofore commonly found in hairpins in that in hairpins as heretofore made a mass of hair frequently becomes wedged between the portions of the legs of the pin adjacent to the bent portion or loop A, which results in the prying apart of the legs so that the end portions are held out of contact. When this occurs, the spring action of the hairpin will tend to cause the hairpin to be displaced lengthwise toward its loop by a wedge action, so that pins of this kind are easily lost out of the hair. In my improved hairpin, however, there is provided lengthwise of the pin a space of substantially uniform width, in which the hair may be located and the inwardly extending projections on the legs will separate the hair into a plurality of strands or groups. Displacement of the pin out of the hair in the direction of the length of the pin will, consequently, be resisted by each of these strands of hair, which would

become wedged in the wedge-shaped or converging angle formed by a leg of the pin and a projection on the opposite leg.

My improved hairpin, consequently, provides between the legs of the pin sufficient space to approximately accommodate the amount of hair passed between the legs of the pin. Consequently, when my hairpin is in place in the hair, the projections of one leg will touch or approximately touch the opposite leg. The hair, therefore, does not cause the legs to be separated to any material extent, and also the pin does not pinch or clamp the hair tightly. The pin, however, has the important function of separating the strand of hair between its legs into several distinct parts by means of the projections, and these parts are each confined in their respective openings in the hairpin. To move the pin lengthwise out of the hair would, consequently, necessitate the changing of the shapes of these several parts of the strands, so that they could pass past the projections of the legs. This, however, requires considerable force, and consequently, the pins are retained in the hair much more firmly than in the case of pins which depend upon a clamping or pressing action of the legs of the hairpin against the hair to hold them in place. The friction between hair and the surfaces of hairpins is very slight, and consequently, pins depending upon such friction are not securely held in the hair, and consequently, my hairpin, which depends not upon the friction between the hair and the pin, but upon the deformation of strands or parts of strands of hair to pass through the small clearance between the end of a projection and the inner surface of a leg of a hairpin, is tenaciously retained in the hair because of the difficulty of deforming such strands, or parts of strands. Furthermore, by increasing the number of projections on the legs of the hairpin, and thus increasing the number of parts into which a strand of hair is divided, a material increase in the holding power of the hairpin results, providing, of course, that the projections are not so numerous as to occupy a large amount of space that should be available for hair. However, for practical purposes only a few projections are necessary to retain the hairpin in the hair.

I have found that a very large percentage of users of hairpins in inserting the pins into the hair, insert between the legs of the pin a quantity of hair of approximately uniform cross sectional area, and that this amount of hair varies but slightly with different users. Consequently, I have designed my hairpin in such a manner that the cross sectional area enclosed between the legs of the hairpin from the loop thereof to the outermost projection or corrugation is just slightly less than the cross section of the average bunch or

strand of hair inserted between the legs of the hairpin. Consequently, in ordinary use, the hairpins described all have the legs thereof only slightly separated and will exert only a relatively slight pressure upon the hair, and because of the fact that comparatively few projections or corrugations are used on my pin, the hair will tend to distribute itself evenly along the length of the pin. I have found that by providing sufficient space or area between the legs of the pin to accommodate most of the hair which is placed between these legs, thus preventing excessive opening or separation of the legs, by the hair clasped by the pin, a very firm gripping of the pin in the hair results, while the hairpin exerts only very slight pressure on the hair.

The hairpins described have the further advantage that they are less visible and more inconspicuous in the hair because of the fact that the legs have fewer corrugations or projections, and consequently, the pins do not reflect light in as many directions.

The projections on the legs of the hairpin may, of course, all be arranged on one leg, but it is preferable to arrange these projections alternately, as shown in the drawing, since a better holding of the pin in the hair seems to result from this arrangement.

I claim as my invention:

1. A hairpin made of resilient material and having a pair of legs spaced apart to a substantially uniform extent by a projection formed on a leg and extending toward an unbent portion of the other leg, said projection forming a definite closure for a space between said legs for confining hair and limiting the pressure of the legs upon the confined hair, the outer surfaces of said legs being free from outwardly extending projections.

2. A hairpin made of resilient material and having a pair of legs spaced apart by projections formed at intervals on said legs, said projections being spaced apart by straight portions of said legs to form between them spaces for confining hair without exerting substantial pressure on the hair.

3. A hairpin made of resilient material and having a pair of legs spaced apart, said legs being provided at intervals with inwardly bent projections, the projections of one leg extending toward the other leg, to form between the legs a series of spaces for confining hair, the outer surfaces of the legs being free from outwardly extending projections.

4. A hairpin having a pair of legs which are spaced apart a substantially uniform distance throughout the greater portion of their length, at least one of said legs having inwardly extending projections arranged at intervals lengthwise of the hairpin, the portions of said legs between said projections being substantially straight and extending into engagement with the other leg, and di-

viding the space between the legs into a plurality of spaces for confining parts of a strand of hair passed between said legs.

5. A hairpin made of resilient material and having a pair of legs spaced apart, each of said legs having projections extending toward a substantially straight portion of the other leg, said projections alternately extending inwardly from opposite legs of the hairpin.

10. A hairpin made of resilient material and having a pair of legs, the greater portions of which are spaced apart by projections formed on a leg and extending toward an unbent 15 portion of the other leg, said projections and the legs of the pin enclosing areas which are slightly less than the cross sectional area of a strand of hair to be passed between the legs of the pin, to cause said legs to exert slight 20 pressure against the confined hair.

25. A hairpin including a pair of legs connected by a loop, said pin being provided at intervals lengthwise thereof with projections extending from one leg to the other, each projection being formed on one of said legs and contacting with a substantially straight part of the other leg and said legs being free from outwardly extending projections.

30. A hairpin including a pair of legs connected by a loop portion, at least one of said legs being provided with projections thereon extending toward a straight portion of the other leg, the projections of a leg being separated by substantially straight portions of 35 the leg, to form a hairpin having a series of definite hair confining areas separated by said projections.

40. A hairpin having a pair of legs spaced apart a substantially uniform distance throughout their lengths and separated by inwardly projecting corrugations alternately disposed on either leg, such corrugations being connected by an unbent portion of the legs and thus forming large defined areas for 45 the inclusion of the hair.

45. A hairpin having a pair of substantially straight parallel legs separated throughout their entire length by inwardly bent projections, said projections being connected by unbent portions of said legs.

50. A hairpin made of resilient material and having a pair of legs provided with projections and spaced apart throughout their entire lengths, except at said projections, said 55 projections on each leg being alternately spaced and dividing the space between the legs into smaller spaces of substantially uniform areas.

60. A hairpin having a pair of legs, alternately arranged inwardly projecting corrugations on said legs, the corrugations of each leg being connected by substantially straight portions of each leg and forming a definite separation between the legs for the purpose 65 of reducing the pressure of the pin on the hair

by forming enclosures of sufficient area to prevent concentrated pressure on the hair between the legs.

13. A hairpin having a pair of curved legs, corrugations formed on a leg and arranged at intervals lengthwise of said leg and extending into contact with the other leg to space said legs at substantially equal distances from each other throughout their length, said corrugations being spaced between uncorrugated portions of the legs to form spaces of material area for confining hair.
